UNITED STATES PATENT OFFICE.

FERDINAND PORSCHE, OF WIENER-NEUSTADT, AUSTRIA-HUNGARY.

VALVE OF INTERNAL-COMBUSTION ENGINES.

1,169,677.

Specification of Letters Patent.

Patented Jan. 25, 1916.

Application filed April 10, 1914. Serial No. 830,881.

To all whom it may concern:

Be it known that I, FERDINAND PORSCHE, engineer and acting manager of the Oesterreichische Daimler-Motoren Aktiengesellschaft, of Wiener-Neustadt, a subject of the Emperor of Austria-Hungary, residing at Wiener-Neustadt, Lower Austria, in the Empire of Austria-Hungary, have invented certain new and useful Improvements in or 10 Relating to Valves of Internal-Combustion Engines, of which the following is a specification.

This invention relates to a type of valve gear for internal combustion engines in which both valves are operated by an oscillating lever actuating the two valves alternately against the influence of a common plate spring.

The feature of novelty resides herein that 20 the plate spring, instead of being mounted as in similar constructions on a stationary member, is attached to the oscillating lever actuating the valves so that it partakes of the movements of the lever. By this means 25 upon the opening of one of the valves the load upon the other valve due to the spring is increased while on the other hand the load upon the opening valve is diminished.

A mode of construction for this arrangement of spring is illustrated in the accompanying drawings as an example, Figure 1 showing the upper part of a cylinder in section and the valves while Fig. 2 is a broken detail view partly in section on the line 35 A—A of Fig. 1.

Referring to the drawing the valves 2 and 3 arranged at the end of the cylinder 1 are supported, by means of projections or abutments 6 on the corresponding valve rods 4 and 5, which engage with the ends of a spring 7 which may be a leaf-spring or plate spring or equivalent adapted to normally hold the valves to their seats. The leaf-spring 7 is supported at its central portion 45 by an oscillating lever 8 adapted to actuate the valves. The lever 8 is rotatably mounted on a pin 9 between standards 10 on the end of the cylinder and when oscillated actuates the valve rods by means of contact portions which may be rounded or formed as curved noses, as illustrated. One arm of the lever which is prolonged is in a known manner pivotally connected to a cam rod 11 subjected to the influence of a cam (not shown) so that the valves are alternately 50 opened by the oscillations of the lever set

up by the cam. The leaf-spring 7 is suitably secured to the lever 8 by providing the lever below its pivot pin with a right-angled eye 12 into which the leaf spring is inserted 60 see Fig. 2 and held fast by a set screw 13 or by a key.

Since the spring is rigidly connected to the lever and therefore endeavors to partake of the oscillating movements of the lever 65 that arm of the spring which engages with a valve in the course of being opened will thus undergo a relaxation of tension and consequently diminish the load upon that valve whereas the other arm of the spring will be 70 subjected to increased tension so that the valve which happens to be in the closed position will be held to its seat with a correspondingly increased pressure. The strength of the spring is so designed that 75 when one valve has been quite opened the maximum pressure affecting the other valve and due to the other portion of the spring corresponds to the spring pressure normally taking effect on the valves when closed and 80 due to a plate spring secured on to a stationary member or to spiral springs as usually employed. The result of this is, that when the lever is in midposition and both valves are therefore closed, the pressure exerted on the valves is considerably less than when the spring is secured to a stationary member that is to say when the spring does not partake of the oscillating movements of the lever so that at the moment when the 85 actuation of the one or the other of the valves commences a considerably lesser resistance has accordingly to be overcome whereby a much quieter and a more elastic operation of the whole valve gear is attained.

While I have described and shown a suitable construction it should be understood that various modifications may be introduced without departing from the scope of 100 my said invention.

What I claim is:—

1. In an internal combustion engine, the combination of admission and exhaust valves, opening means for actuating said 105 valves alternately to open them alternately, and elastic means tending to close said valves controlled by the operation of said opening means so that the tension and load on a closing valve is increased, while the load on 110 an opening valve is diminished.
2. In an internal combustion engine, the

combination of admission and exhaust valves, an oscillating lever for actuating said valves alternately to open them alternately, and elastic means for closing said valves alternately and partaking of the oscillating movements of said lever, whereby the load on a closing valve is increased while the load on an opening valve is diminished.

3. In an internal combustion engine, the combination of admission and exhaust valves, an oscillating lever for opening said valves alternately, and a plate spring for closing each of said valves, when said valves are released by said lever, said spring partaking of the oscillating movements of said lever, whereby the load on a closing valve is increased while the load on an opening valve is diminished.

4. In an internal combustion engine, the combination of admission and exhaust valves, an oscillating lever for opening said valves alternately, and a plate spring adapted when said lever is in mid-position, to hold both of said valves closed with equal pressure, and to oscillate in unison with said lever, as it moves from said mid-position, whereby the load on a closing valve is increased while the load on an opening valve is diminished.

5. In an internal combustion engine, the combination of admission and exhaust valves, an oscillating lever for opening said valves alternately, and a plate spring tending to close said valves, and secured to said lever so as to partake of its oscillating movements, thereby increasing the load on one of said valves when closed and diminishing the load on the other valve.

6. In an internal combustion engine, the combination of admission and exhaust valves, an oscillating lever for opening said

valves alternately, a pivoted plate spring tending to close said valves, and means whereby said spring is caused to oscillate in unison with said lever, whereby the load on a closing valve is increased while the load on an opening valve is diminished.

7. In an internal combustion engine, the combination of admission and exhaust valves each valve being provided with a stem, and a pivoted lever adapted when oscillated to actuate said stems alternately so as to open the corresponding valve, abutments on the free ends of said stems, a spring having each end adapted to engage with the abutments on the corresponding stem, a seating for said spring centrally located on said lever with respect to its length, and means for rigidly securing said spring to said seating.

8. In an internal combustion engine, admission and exhaust valves, opening means for actuating said valves alternately to open them alternately, said opening means moving toward said valves to open them, and withdrawing from said valves when said valves are to remain closed, elastic means constantly tending to maintain said valves in a closed position, and connecting means intermediate said elastic means and said opening means, said connecting means causing the force of said elastic closing means for said valves to be less when said opening means are moving toward said valves than when said opening means are moving away from said valves.

In witness whereof I have hereunto set my hand in presence of two witnesses.

FERDINAND PORSCHE.
